UNITED STATES PATENT OFFICE.

FRANK M. STEINER, OF MINNEAPOLIS, MINNESOTA, ASSIGNOR TO STEINER SALES COMPANY, OF SALT LAKE CITY, UTAH, A CORPORATION OF UTAH.

TOWEL CABINET.

Application filed October 18, 1920, Serial No. 417,740. Renewed July 14, 1922. Serial No. 574,980.

To all whom it may concern:

Be it known that I, FRANK M. STEINER, a citizen of the United States, resident of Minneapolis, county of Hennepin, State of Minnesota, have invented certain new and useful Improvements in Towel Cabinets, of which the following is a specification.

The object of my invention is to provide a towel cabinet in the construction of which all gears and rolls are eliminated, thereby reducing materially the initial cost of the cabinet and the expense of its upkeep.

A further object is to provide a cabinet that is easily accessible for the purpose of inserting a roll of clean toweling and removing the soiled portion, and a cabinet of such simplicity of construction that a person totally unfamiliar with devices of this kind would have no trouble in placing the clean towel therein and putting the device in condition for immediate and convenient use.

A further and particular object is to provide a cabinet of such construction that the soiled towel when released by the user will always fall into the chamber provided to receive it, as soon as released by the user.

A further object is to provide a cabinet in which provision is made to prevent the solid portion of the towel from coming in contact with the clean portion at any time during the use of the device.

Other objects of the invention will appear from the following detailed description.

The invention consists generally in various constructions and combinations, all as hereinafter described and particularly pointed out in the claims.

In the accompanying drawings forming part of this specification,

40 Figure 1 is a vertical sectional view through a towel cabinet embodying my invention,

Figure 2 is a sectional view on the line 2—2 of Figure 1.

45 In the drawing, 2 represents the lower portion of the base of the cabinet, having supporting legs 3 and provided with a clean towel chamber 4. An opening 5 is provided in the top of the base, through which the roll of toweling is inserted. 6 represents the rear wall of the base, having an outwardly turned upper portion 7 between which and a depending flange 8 an opening is provided for the end of the towel. The end 7 preferably laps by the lower edge of the flange 8

and has sufficient tension to grip the towel with a yielding pressure, allowing it, however, to be drawn freely through the opening as it is required for use. The flange 8 is preferably formed from the upper portion of the base, depending from a rail thereof in the rear of the opening 5.

9 represents the soiled towel container, having a closed bottom and preferably hinged at 10 to the front wall of the base, 65 said container having an open top and provided with upwardly projecting straps 11 supporting a cross rod 12 over which the loose or free end of the towel is adapted to slide. Straps 11 preferably have outwardly 70 turned lower ends 13 adapted to contact with the wall against which the cabinet is placed and form guides for the strip of toweling moving vertically between them.

When the container 9 is tilted forward, as 75 indicated by dotted lines in Figure 1, the opening 5 is exposed and a roll of toweling may be inserted into the chamber 4. Then when the soiled towel container is tilted back to a horizontal position, as indicated 80 by full lines in Figure 1, the opening 5 will be closed and the clean toweling will thereby be protected from dust and dirt. The user, standing in front of the cabinet, will draw on the loose end of the towel and as 85 fast as it is used, the soiled portion will be allowed to drop into the container 9, as indicated in Figure 1, until the roll of clean toweling is entirely used up. The container will then be emptied of its contents and the 90 soiled towel returned to the laundry and a clean roll placed in the chamber 4.

In a towel cabinet of this type where yards of continuous towel are used, it is very important that the cabinet be constructed so 95 that as the clean web is drawn out and used, and then released or dropped by the user, it will fall down by itself into the compartment within the cabinet provided to receive it without any action or attention whatsoever on the part of the user. Persons using a towel cabinet are usually in a hurry, a hasty pull is imparted to the clean towel web, the wiping operation performed and the towel web dropped as the user leaves 100 the cabinet, and unless provision is made for the automatic deposit of the soiled towel in its proper chamber, the web would soon be hanging outside of the cabinet or trailing 105 on the floor of the washroom. A very es- 110

ential feature of this cabinet, therefore, is the position and relative arrangement of the clean towel roll chamber, the support for the clean towel web and the delivery opening 5 so that the user may have convenient access to the towel, and when he is through with it, the soiled portion will drop of its own weight into the chamber and be concealed from view.

- 10 To provide a cabinet of this kind, it is necessary that sufficient space be arranged for at the top for the delivery of the web of clean towel and the automatic deposit of the soiled portion in its chamber as fast as 15 used and released by the user. Applicant is able to produce a cabinet of this type by mounting his clean roll in the base, stretching the web thereof upwardly over a suitable support in the rear of the delivery 20 opening so that the clean towel can be easily obtained, and when released, the soiled portion will drop into the chamber below the opening.

The wall 6 exerts sufficient tension on the 25 loose end of the towel so that it will not feed too freely when pulled, particularly when the towel is nearly unrolled and to this extent the function of the wall 6 corresponds to the element 8 in my companion 30 application executed October 11, 1920, filed October 16, 1920, Serial No. 417,466.

I claim as my invention:

1. A towel cabinet comprising a base having a chamber for the clean towel and an 35 opening in its wall through which the loose end of the clean towel is passed, the top of said base having an opening for the insertion of the clean towel, a soiled towel container surmounting said base and normally closing 40 said opening, said container having an open top through which the soiled towel falls into said container, and means for supporting the loose end of the towel above said container and over which means the clean towel is pulled as it is used.

2. A towel cabinet comprising a base having a chamber therein to receive the clean towel and an opening in its wall through which the loose end of the clean towel is inserted, a soiled towel container hinged at its lower forward portion to said base and adapted to tilt forwardly to allow the insertion of the clean towel into said chamber and said container having an open top through which the soiled end of the towel falls after it is used, and means above said container for supporting the loose end of the towel and over which means the towel is pulled by the user.

3. A towel cabinet comprising a base having a chamber therein to receive the clean towel and an opening in its wall through which the loose end of the clean towel is inserted for withdrawal from said chamber, a soiled towel container surmounting said base and adapted to receive the soiled end of the towel as it is used, straps mounted on said container and projecting above the same and having a cross bar between them over which the loose clean end of the towel is drawn, said straps having means between which the clean end of the towel is fed and guided.

4. A towel cabinet for a loose-end continuous towel comprising a chamber in its lower portion for the roll of the clean towel, an upper compartment open for the delivery of the clean towel the web of clean towel being stretched upwardly in the rear of said cabinet, a support in the upper portion of said cabinet over which the loose web of clean towel is drawn by the user to said open compartment wherein the soiled portion of the towel falls in folds when it is released by the user standing in front of the cabinet, the rear wall of said compartment separating the clean portion of the towel from the folds of the soiled towel.

5. A towel cabinet, comprising a casing having a chamber therein to receive the clean towel, and an opening in its wall through which the loose end of the clean towel is fed, a soiled towel container, normally closing the top of said chamber and adapted to be moved to allow the insertion of a clean towel into said chamber, said container having an open top through which the soiled portion of the towel falls as it is used, and means above said container over which the loose end of the clean towel is pulled by the user.

6. A towel cabinet comprising a casing having a chamber in its lower portion for the supply of clean towel and a support in its upper portion over which the web of clean towel passes to the user, said cabinet also having a chamber adjacent the clean towel receptacle for the soiled towel and an opening above said soiled towel chamber through which the user may conveniently grasp and pull the clean web, said opening being so positioned with respect to said soiled towel chamber that the towel when used and released will automatically fall therein.

In witness whereof I have hereunto set my hand this 13th day of October, 1920.

FRANK M. STEINER.
